UNITED STATES PATENT OFFICE.

EDWARD M. RICHARDS, OF WEST ORANGE, NEW JERSEY, ASSIGNOR TO THOMAS A. EDISON, INCORPORATED, OF WEST ORANGE, NEW JERSEY, A CORPORATION OF NEW JERSEY.

DESIGN FOR A GRILLE FOR PHONOGRAPH CABINETS.

Application filed November 3, 1927. Serial No. 23,995. Term of patent 7 years.

To all whom it may concern:

Be it known that I, EDWARD M. RICHARDS, a citizen of the United States, residing at West Orange, in the county of Essex and State of New Jersey, have invented a new, original, and ornamental Design for a Grille for Phonograph Cabinets, of which the following is a specification, reference being had to the accompanying drawing, forming a part thereof.

The figure is a plan view of a grille for phonograph cabinets showing my new design.

I claim:

The ornamental design for a grille for phonograph cabinets as shown.

EDWARD M. RICHARDS.
